MINER'S LAMP

Grant Wheat, Marlboro, Mass., assignor to Koehler Manufacturing Company, Marlboro, Mass., a corporation of Massachusetts

Application December 28, 1932, Serial No. 649,146

6 Claims. (Cl. 240—11.3)

This invention relates to miner's lamps and other portable lamps of essentially the same general character.

It aims to improve lamp apparatus of this type with a view to simplifying its construction and reducing the expense of manufacture, while at the same time protecting it from accidental short circuiting and from mischievous tampering by the miners themselves.

10 The nature of the invention will be readily understood from the following description when read in connection with the accompanying drawings, and the novel features will be particularly pointed out in the appended claims.

15 In the drawings,

Figure 1 is a perspective view of a portion of a novel battery charging rack and illustrates a miner's lamp constructed in accordance with this invention located in charging position in

20 said rack;

Fig. 2 is a horizontal, sectional view through a portion of the rack shown in Fig. 1;

Fig. 3 is a perspective view showing details of the connector which is included in the circuit 25 connections between the battery and the headpiece of the lamp; and

Fig. 4 is a rear elevation of the headpiece and the connector, the casing enclosing the connector being shown in section.

30 Referring first to Fig. 1, the miner's lamp there shown comprises a storage battery, indicated in general at 2, a headpiece 3, and a cord or cable 4 including conductors which supply current from the battery to the electric lamp 5 in the headpiece 3. The headpiece is shown more in detail in Figs. 3 and 4. It is designed to be worn on the miner's cap and for this purpose is provided with a spring clamp 6 for attachment to a plate with which the cap is equipped. In general organization this lamp resembles that shown and described in my earlier patents, such, for example, as my Patent No. 1,757,887, granted May 6, 1930. The headpiece, in addition to carrying a main electric lamp 5, also is equipped with a

45 smaller emergency lamp 7, Fig. 1, which gives light enough to enable the miner to see his way out of the mine in the event that the main lamp burns out, and the headpiece is equipped with a switch arranged to be operated by the knob 8, Figs. 3 and 4, so that the miner can turn either lamp bulb 5 or 7 on or off, as he desires.

50 Since the battery 2 is of the secondary type it must be re-charged at intervals. This has been conveniently accomplished heretofore by locating charging terminals in some exposed position

on the battery or the headpiece, providing a switch for controlling the connection between these terminals and the battery terminals, and locking the switch so that the miners can not operate it and thus render the charging terminals "alive". According to the present invention, however, both the switch and its locking means are eliminated from the battery and the headpiece, and a connector is included in the circuit between the battery and the headpiece, this connector comprising parts which may be separated to disconnect the headpiece from the battery both electrically and mechanically.

55 Referring more particularly to Figs. 3 and 4, the connector there shown comprises two members 10 and 12, respectively, both made of insulating material. One forms a part of the headpiece assembly and is equipped with metal pins 13 insulated from each other, while the other forms the terminal for the cord and is provided with metal sockets or thimbles 14 to receive the pins 13. In the particular arrangement shown the pins are mounted on the part 12 and are connected to the conductors which lead through the switch above described to the electric lamps 5 and 7, the part 12 being rigidly secured to and forming the end of the shank or neck of the headpiece 3. The two metal socket members 14 are connected, respectively, to the two conductors in the cord 4, and the insulating member 10 is rigidly secured to the end of this cord. When the two parts of the connector are brought together in their closed relationship with the pins 13 entered in the sockets 14, as shown in Fig. 4, the apparatus then is in condition to be 20 used in exactly the same manner as the miner's lamp shown in my prior patent above designated.

60 It is important to lock the connector in its closed position by some means which cannot be operated by the miner so that the contacts and those parts which carry current will not only be protected against accidental short circuiting, with the consequent danger of producing a spark which might cause an explosion if inflammable 45 gas were present, but, in addition, to prevent the miners from tampering with the conductors and thus creating a short circuit either accidentally or intentionally. For this purpose two hook-shaped latches 15—15 are pivoted on the 50 headpiece at opposite sides of the connector member 12 and are arranged to engage shoulders in opposite sides of the connector member 10 formed by notching this member as shown at 16. Access to these latches or locking members nor- 55

mally is prevented by the fact that they are enclosed in a sheet metal casing 18. Each latch has a spring 17 associated with it and bearing against the casing to hold the hook of the latch 5 in its respective notch 16.

It will be seen from an inspection of Fig. 4 that one end of the casing 18 is provided with a bottom through which an aperture is formed of such a size as to receive the reduced portion 10 of the connector member 10, the portion of the casing immediately around this aperture bearing against a shoulder 20, Fig. 3, formed on said member. Consequently, when the parts of the connector are pushed together to close the connector, the hooks of the latches 15—15 snap into the notches 16—16 and lock the parts in their closed relationship, as shown in Fig. 4. This operation also locks the casing in its operative position since the latches must first be released before 20 the parts of the connector can be separated to release the casing. The casing thus prevents access either to the locking means or to the parts of the connector in which the contacts are located.

The locking mechanism may be operated to 25 release the latches by bringing a horse-shoe magnet or an electro-magnet into such a position that its poles lie at opposite sides of the casing 18 and outside the two hooks. The casing should be made of some non-magnetic material such as 30 brass, aluminum, or the like, while the latches are made of some magnetic material, such as iron or steel. The poles of the magnet thus will draw the latches outwardly, releasing them from the shoulders of the notches 16—16 and permitting 35 the separation of the connector members simply by pulling on the cord 4 while holding the headpiece 3.

It is contemplated that when the miner turns 40 in his lamp at the lamp house upon leaving the mine, the lamp house attendant will remove the headpiece and then place the apparatus in the charging rack, as shown in Fig. 1. This rack includes a lower shelf 22 for supporting the batteries and an upper shelf 23 on which the headpieces may be placed. Preferably a guide 24 is 45 associated with the lower shelf and is provided with a series of notches 25, each of suitable width to receive an individual battery. Associated with the upper shelf 23 is an upright panel 50 26 carrying a series of pairs of pins 27, each pair corresponding in dimensions to the pins 13, Fig. 3, of the connector. These pins are connected in series in a charging circuit by means of metal strips 28 secured to the back of the panel. Consequently, by plugging the socket member 10 on 55 to any pair of pins 27 the battery will be connected into the charging circuit.

If a constant current series charging system is used, it is necessary to provide some means for 60 closing the circuit between those pins 27 which are not in use. This is conveniently accomplished in the construction shown by associating two spring contacts 30 with each pair of pins and connecting the lower ends of the contacts adjacent to the points at which they are affixed to 65 the panel 26 by a coil 31 of wire having a resistance corresponding substantially to that of a battery. Preferably the upper ends of these spring members are bevelled, as best shown in 70 Fig. 2, so that when the socket member 10 is pushed on to the pins it will force the contacts apart and thus interrupt any flow of current through the resistance coil 31. When the socket member 10 is withdrawn the contacts 30 will spring back 75 into contact with the pins 27 and thus will auto-

matically close the circuit again through these pins, thus short circuiting them. It will be noted that one of each pair of pins 27 is larger in diameter than the other and that the sockets in the connector 10 differ correspondingly in diameter 5 so that there is no possibility of reversing the polarity of the battery during the charging operation. Because of this arrangement the pins 13 differ likewise in size.

The invention thus provides a miner's lamp 10 structure which is simplified substantially as compared with the more common lamps of this character now on the market, while at the same time being amply protected against short circuiting either accidentally or intentionally. In addition, 15 the nature of this construction is such that it permits the use of an extremely simple form of charging rack. It also facilitates the interchange and substitution of one headpiece for another in the event that an individual headpiece requires 20 pairs. A similar interchange of batteries for an individual headpiece can be made if trouble should develop in the battery.

While I have herein shown and described a preferred embodiment of my invention, it will be evident that the invention may be embodied in other forms without departing from the spirit or scope thereof. For example, some other form of lock could be substituted for the magnetically releasable lock used with the connector, the essential point 30 being that the locking means shall require the use of a key, magnet, or some other tool of an unusual character which the miner will be very unlikely to have.

Having thus described my invention, what I desire to claim as new is:

1. In a miner's lamp, the combination with a headpiece, an electric lamp mounted in said headpiece, a storage battery, and a cord for connecting said battery with said headpiece and including conductors for supplying current to said lamp, of a connector having contacts in circuit with said conductors, said connector having parts readily separable from each other to open the circuit and to disconnect said headpiece both mechanically and electrically from said battery, a lock for holding said connector closed, and a casing preventing access to said lock, said casing also being held closed by said lock.

2. In a miner's lamp, the combination with a headpiece, an electric lamp mounted in said headpiece, a storage battery, and a cord for connecting said battery with said headpiece and including conductors for supplying current to said lamp, of a connector having contacts in circuit with said conductors, said connector having parts readily separable from each other to open the circuit and to disconnect said headpiece from said battery, and a normally inaccessible lock for holding said connector closed, said lock being arranged to be released by the presentation thereto of a magnet in a predetermined relationship to the lock.

3. In a miner's lamp, the combination with a headpiece, an electric lamp mounted in said headpiece, a storage battery, and a cord for connecting said battery with said headpiece and including conductors for supplying current to said lamp, of a connector having contacts in circuit with said conductors, said connector having parts readily separable from each other to open the circuit and to disconnect said headpiece from said battery, a spring operated latch for locking said parts of said connector against separation, and a casing preventing access to said latch, said 75

casing and latch being so arranged that the latch may be released by holding a magnet in a predetermined relationship to the casing.

4. In a miner's lamp, the combination of a headpiece, an electric lamp mounted in said headpiece, a cord for connecting a storage battery with said headpiece and including conductors for leading current to and from the headpiece, a connector having contacts in circuit with 5 said conductors and including two members, one of which forms a part of the headpiece assembly and the other forming a terminal for said cord, said members being readily separable from each other to open the circuit and to disconnect said 10 headpiece both electrically and mechanically from said cord and battery, means for locking said connector in its closed condition, including means for preventing the separation of said members except through the use of a special tool, 15 and means for preventing access to said locking 20 means and to said contacts.

5. In a miner's lamp, the combination of a headpiece, an electric lamp mounted in said headpiece, a cord for connecting a storage battery with said headpiece and including conductors for leading current to and from the headpiece, a connector having contacts in circuit with 25 said conductors and including two members, one

of which forms a part of the headpiece assembly and the other forming a terminal for said cord, said members being readily separable from each other to open the circuit and to disconnect said headpiece both electrically and mechanically from said cord and battery, a casing enclosing said contacts and preventing access to them, and normally inaccessible means for locking said casing in its operative position. 5

6. In a miner's lamp, the combination of a headpiece, an electric lamp mounted in said headpiece, a cord for connecting a storage battery with said headpiece and including conductors for leading current to and from the headpiece, a connector having contacts in circuit with 10 said conductors and including two members, one of which forms a part of the headpiece assembly and the other forming a terminal for said cord, said members being readily separable from each other to open the circuit and to disconnect said 15 headpiece both electrically and mechanically from said cord and battery, and a normally inaccessible lock for holding said connector closed, said lock being arranged to be released by the presentation thereto of a magnet in a predetermined relationship to said lock. 20 25
